SPINNING MACHINE

Application filed September 21, 1928. Serial No. 307,388.

This invention relates to spinning or roving machines and more particularly to a device which may be embodied in a spinning machine for preventing double spinning.

5 In spinning operations, a thread is drawn from each of a plurality of spaced spools and guided separately to one of a plurality of rapidly rotating spindles upon which it is wound while being spun. It often happens that one of the threads becomes broken and entangled with another thread. If this is permitted to take place two threads are spun together and wound upon the same spindle resulting in what is commonly known as 10 double spinning. Double spinning is objectionable chiefly for the reason that when the thread is employed in the manufacture of cloth there are lines in the cloth which contain threads of a non-uniform size which is a defect either causing rejection of the cloth or materially lessening its value.

It is an object of the present invention to overcome these difficulties and provide a device of simple construction which may be embodied in the ordinary spinning or roving machine to prevent double spinning or roving and which is particularly adapted for use in a cap spinning machine. In accordance with the invention a device is arranged between 25 adjacent threads being spun so that if one thread becomes broken and entangled with another it will be caught and held until the action of spinning a thread twists it off and thus disconnects the two threads. A suitable 30 device for this purpose may comprise an arm adapted to reciprocate between adjacent threads and which is provided at its end with a plate containing a wedge shaped notch adapted to catch and hold a thread which 35 becomes entangled with another. In accordance with the preferred construction the plate is curved upon its forward edge so as to guide the thread to the rear edge of the plate which is provided with one or more thread-holding 40 notches.

The invention is illustrated as applied to a cap spinning machine in which the threads are spun continuously upon rotating spindles and in which the device for preventing double spinning reciprocates continuously between

adjacent threads. It will be understood, however, that the invention is applicable to other types of spinning and roving machines, such as the ring and flyer types, and is not limited to the specific type described.

55 The invention will be more clearly understood from the following description in conjunction with the accompanying drawings; in which,

Fig. 1 is a side elevational view, partly broken away, of a cap spinning machine embodying the invention;

Fig. 2 is a plan view of a portion of the same;

Fig. 3 is a detail view of the device adapted to engage and hold the thread when it becomes entangled with another; and

Fig. 4 is a fragmentary perspective view of the spinning machine showing the device holding a thread entangled with another while being twisted.

In the accompanying drawings a cap spinning machine is illustrated comprising a frame 10 upon which are mounted a plurality of upwardly extending spindles or pegs 11 each adapted to receive for rotation thereon a spool 12 containing a supply of roving T to be spun. A cross shaft 15 is mounted for rotation in suitable bearings in the frame 10 and is provided with a plurality of spaced 20 rolls 16. The frame 10 is provided at spaced points with aligned upwardly extending guide arms 17 adapted to support for rotation a shaft 18 provided with a plurality of spaced rolls 19 which engage and cooperate with the rolls 16 to draft the thread from the spools 12. A second series of spaced stationary spindles 20 each provided with a hollow cap 21 are mounted upon the frame 10. Each spindle 20 is arranged to receive a tube 25 which may be operatively connected for rapid rotation, as for example, to a pulley 22 mounted upon each tube 25 for rotation by a belt 23. If desired a guide 26 may be positioned upon the frame 10 to receive and guide the rovings 25 from each of the spools 12 in a suitable direction to be received between the proper draw rolls 16 and 19. The shaft 15 may be rotated continuously by any suitable mechanism, not shown.

In accordance with one application of the invention an eccentric 30 may be mounted upon the shaft 15 to rotate therewith. An eccentric strap 31 is arranged to engage the eccentric 30 and is connected at its free end to one end of a link 32 the other end of which is fixed upon a shaft 33 which is mounted for rotation in suitable bearings in the frame 10. A plurality of links 35 are secured in any suitable manner in spaced relation upon the shaft 33 and each is provided at its free end with swivel connection 34 adapted to receive an arm 36 arranged to reciprocate in substantially a given plane between adjacent threads. With this in view each arm 36 is supported for reciprocatory movement in an opening 8 in a cross member 9 of the frame. A suitable clamping device is provided upon the free end of each arm 36 and is adapted to engage and hold a thread which becomes broken and entangled with another thread. For this purpose each of the arms 36 is provided with a plate 37 provided with one or more wedge shaped notches 38 arranged so that a thread may be wedged therein and held. Preferably, the plate 37 is provided with a curved forward edge 39 so as to engage and guide a thread toward the rear edge of the plate.

In the operation of the machine, the shafts 15 and 18 are caused to rotate continuously by suitable mechanism not shown and power is transmitted through belts 23 to rotate the tubes 25. In the normal operation of the machine a roving is drawn from each of the spools 12 through a separate pair of cooperating rolls 16 and 19 and is twisted and wound upon one of the tubes 25. If for any reason one of the threads becomes broken and entangled with another thread, as shown in Fig. 4, double spinning will result unless that thread is broken. In the operation of the device of the invention the thread which thus becomes broken and entangled with another is engaged by the curved forward edge 39 of the plate 37 which guides it to the rear edge thereof whereupon it is caused to spring into one of the notches 38 in which it becomes wedged and held. As the spinning of the thread continues it is twisted off and thus broken thereby separating the two entangled threads and preventing double spinning.

The device of the invention is of simple construction and while it is particularly adapted for a cap spinning machine it can be used upon any type of spinning or roving machine. Its action is positive and dependable because it merely holds the thread while the action of the machine twisting the thread causes the latter to break whereas prior devices of this character have relied upon a knife-like instrument for cutting the thread. These prior devices have not been wholly satisfactory because they often failed to cut the thread. Throughout the appended claims

the term spinning is intended to cover roving as well as spinning.

What we claim is:

1. In a spinning machine having spaced cooperating pairs of draw rolls, each pair cooperating with similarly spaced spindles to supply a thread to each of said spindles, and means for rotating said spindles continuously to twist said threads separately, the combination therewith of a plate positioned between said threads and provided on its inner edge with a notch, and means for reciprocating said plate in a path substantially perpendicular to the plane of said threads to move the crotch of said notch inwardly towards said plane a limited amount to wedge therein a portion of one thread and hold it against rotation whereby said thread becomes broken solely by its own twisting action.

2. In a spinning machine having spaced cooperating pairs of draw rolls, each pair cooperating with similarly spaced spindles to supply a thread to each of said spindles, and means for rotating said spindles continuously to twist said threads separately, the combination therewith of an arm, a plate supported between said threads by one end of the arm and having a notch on its inner edge, means for guiding said arm for movement in a path substantially perpendicular to the plane of said threads, and means connecting the other end of the arm for reciprocating the same to move the crotch of said notch inwardly towards said plane to wedge therein a portion of one thread and hold it against rotation whereby said thread becomes broken solely by its own twisting action.

In testimony whereof we affix our signatures.
